UNITED STATES PATENT OFFICE

ROBERT EARL DAWES, OF BOZEMAN, MONTANA

CLOSURE LOCK

Application filed November 1, 1929. Serial No. 404,055.

The present invention relates to improvements in means for locking closures and more particularly to an electro-magnetic lock for gasoline tank filler caps.

5 The principal object of the invention is to provide a lock for gasoline tank caps which may be unlocked by switch means located on the instrument board of the vehicle so as to eliminate the necessity of the driver leaving the vehicle when replenishing his fuel supply at a gasoline station.

10 During the course of the following description and claim numerous other important objects and advantages of the invention will readily become apparent.

In the drawings:

Figure 1 represents a fragmentary longitudinal sectional view through a portion of an automobile showing the disposition of the 15 present invention.

Figure 2 represents a diagrammatic view of the electrical circuit and the constituent electrical devices.

Figure 3 represents a fragmentary vertical sectional view through a gasolene tank equipped with the improved lock means for its closure.

Figure 4 represents a cross sectional view taken substantially on line 4-4 of Figure 3.

Figure 5 represents a fragmentary sectional view taken substantially on the same line as Figure 4, but showing the bolt in retracted position.

Figure 6 represents a fragmentary sectional view taken substantially on line 6-6 of Figure 3 and looking in the direction of the arrows.

Figure 7 represents a fragmentary sectional view looking toward the recess of the cap for receiving the bolt.

Figure 8 represents a fragmentary sectional view taken substantially on line 8-8 of Figure 3 and looking in the direction of the arrows.

Figure 9 represents a perspective view of the armature bolts of the lock.

Referring to the drawings wherein like numerals designate like parts, it will be seen that numeral 5 denotes the usual cowl portion of an automobile body, while 6 repre-

sents the usual instrument board. The chassis of the automobile is designated by numeral 7 and to the chassis is secured or suitably mounted a battery 8. Toward the rear end of the chassis and secured thereto is the usual fuel tank 9 from which the neck 10 protrudes. The upper end of the neck 10 has a circumferentially extending shoulder 11 at a point inwardly from its extremity and hingedly secured to this shoulder 15 as at 12 is the cap 13 having the usual vent 14.

At the inner side of the cap at a point diametrically opposite from the hinge 12 is a socket 15 registerable with an opening in the adjacent side portion of the neck 10. The upper portion of the neck at this point recedes as at 16 and a partition 17 disposed within the neck 10 is of arcuate cross section and extends upwardly in the manner shown in Figure 3. The upper portion of this partition 20 converges to meet the receding portion 16 of the neck 10 so as to provide a closed compartment 18.

Mounted within the closed compartment is a cross member 19, while to the partition 17 adjacent the upper end thereof and within the confines of the chamber 18 is a magnetic coil 20. An armature bar 21 is hingedly connected to the cross member 19 as at 22 and a bolt 23 having its outer end bevelled as at 24 extends laterally from the free end of the said bar. This bolt is engageable through the aforementioned opening in the neck 10 and into the socket 15 of the closure 13 when the said socket is registered with the said opening.

A spring 25 serves to tensionally urge the bolt through the opening in the neck and always maintains the closure locked against displacement. A plate 26 is provided on the opposite side of the bar 21 from the bolt 23 and in opposed relation with respect to the core of the magnet 20.

A key operated switch 27 is provided on the instrument board and from one side of this switch a conductor 28 extends to the magnet 20. A lead 29 extends from the positive side of the aforementioned battery 8 through a fuse 30 to the remaining side of the switch 27, while a connection 31 is made 35 to the negative side of the battery 8.

between the negative side of the battery and the remaining side of the said magnet 20.

It will thus be seen that when the switch 27 is closed by means of the proper key 32, the magnet 20 will become energized and attract the bar 21. The attraction of the bar 21 will disconnect the bolt 23 from the socket 15 of the closer 13, thus permitting the closer to be lifted. The switch may then be opened 10 so that when the closer is again permitted to gravitate to its closed position, the bevelled bolt 23 will engage automatically within the socket 15 to again secure the closer.

While the foregoing description specifically sets forth the invention, it is to be understood that various changes in the shape, size and materials may be resorted to without departing from the spirit and scope of the invention as claimed hereinafter.

Having thus described the invention, what is claimed as new is:

A closure fastener for containers having a filler neck comprising a partition for dividing the interior of the filler neck, said partition being shaped to provide a closed compartment in the filler neck, a closure engageable bolt slidable through the side of the neck from the compartment, a swingable arm for carrying the bolt at its free end, said arm being mounted and operative in the compartment, a spring in the compartment for normally maintaining the bolt projected toward the closure, and means in the compartment for retracting the bolt when desired.

In testimony whereof I affix my signature.
ROBERT EARL DAWES.
